MOUNTING DEVICE ARRANGED IN LOOM
SHUTTLES FOR THE WINDING SUPPORTS,
PARTICULARLY FLAT WINDING SUPPORTS

Georg Wiget, Arbon, Switzerland, assignor to Société Anonyme Adolphe Saurer, Arbon, Switzerland

Application December 21, 1943, Serial No. 515,080
In Switzerland December 23, 1942

9 Claims. (Cl. 139—209)

This invention relates to loom shuttles and more especially to the means for supporting in the shuttle body the spindle carrying the bobbin.

It is an object of my invention to provide a shuttle comprising particularly effective means for securely mounting the spindle in the shuttle body, for locking it therein and for facilitating the release and withdrawal of the spindle after consumption of the thread carried by the spindle.

With this end in view, I provide a spindle support fixed to the shuttle body and I form the bottom end of the spindle in such manner that it can be seated securely and without play in the support.

I also provide means pivoted to the shuttle body adapted to grip the spindle about to be mounted in the support, to pull the spindle down onto its seat and to lock it in the seat.

I further organize the spindle and the locking means in such manner that movement of the locking means in a direction counter to the locking direction helps disengage the spindle from its seat and thereby facilitates its removal.

An embodiment of the present invention is illustrated diagrammatically by way of example in the accompanying drawing in which:

Fig. 1 is a longitudinal section of a shuttle, with a flat spindle about to be mounted therein;

Fig. 2 is a longitudinal section with the spindle mounted in working position;

Fig. 3 is a plan view of Fig. 2;

Fig. 4 is a view drawn to a larger scale of the seating end portion of the spindle as viewed from above;

Fig. 5 is a cross section on the line V—V in Fig. 4, and

Fig. 6 is a horizontal sectional view of a modified form of the seating end of the spindle.

The seating end of the flat spindle 10 is formed with a frusto-conical extension 11 which may have a circular cross-section. This extension fits in a funnel-shaped seat 14 formed in the bridge piece 20 which extends across the cavity 2 of the shuttle body 1. The extension 11 is provided with a cross-bore 12 ending in lateral longitudinal grooves 13, 13' formed in the circumference of the extension 11.

When the spindle shall be mounted in the shuttle, the socket 11 is introduced into the funnel-shaped seat 14, as shown in Fig. 1, being guided during this movement by the locking member or dip 8 whose hook-shaped end enters one of the two longitudinal grooves 13, 13' of the extension 11 and the cross-bore 12.

This locking member 8 is a metal clip formed

like an interrogation mark, its threaded bottom end 9 being fixed in an arm 7 pivotally mounted on a pin 6 which extends between the parallel shanks 3 of a horse-shoe shaped toggle lever 4 mounted on an axle 5 seated in the shuttle cavity.

In the "open" position of the parts shown in Fig. 1 the guiding, locking and releasing device comprising the toggle lever 3, 4 and the clip 8 is ready to guide, grasp, pull in and lock the spindle. When the flat portion of the toggle lever is moved to rock the lever towards the left, the hook-end of the clip 8 enters the bore 12 of the spindle extension 11, gripping the extension-bottom 21 and pulling it towards the left, thereby forcing the extension to firmly seat itself in the funnel-shaped seat 14 formed in the bridge 20. When the toggle lever has reached its end position, shown in Fig. 2, the arm 7 abuts against an inclined face 22 on the bridge piece 20, thereby locking the threaded bottom end and the middle section 23 of the clip 8 which now rests on another inclined face 24 of the bridge piece, in a position approaching the horizontal, and the hook-end 25 of the clip in vertical position whereby the spindle extension 11 is held down on its funnel-shaped seat 14.

On the other hand, if the spindle is to be removed from the shuttle, rocking the lever 4 to the right not only unlocks the extension 11, but also pushes it away from its seat by the hook-end 25 of the clip 8 exerting pressure on the top wall 26 of the bore 12 until the middle section 23 of the clip comes to rest on the funnel-shaped seat in the bridge piece, thereby allowing the spindle extension 11 to pass through between the bottom 24 of the bridge piece and its inwardly projecting parts 28 which also provide an abutment 29 for the toggle lever in its "open" position.

40 In the modified form shown in Fig. 6 the spindle extension 11', contrary to what is shown in Fig. 5, has a rectangular cross-section, and so has its seat 14', whereby the spindle is prevented from turning in its seat.

45 I wish it to be understood that I do not desire to be limited to details of design shown and described, for obvious modifications will present themselves to a person skilled in the art.

I claim:

50 1. In a loom-shuttle in combination, a shuttle body formed with a cavity adapted to house a spindle, a bridge piece in said cavity offering a seat for the bottom end of a spindle, a hook-shaped clip arranged near one end of said cavity and a toggle lever arranged to rock about an

axis extending across said cavity, and operatively connected with said clip to pull and push it, respectively, in the longitudinal direction of said shuttle body and the spindle seat formed therein and to lock the spindle in its seat.

2. In a loom-shuttle in combination, a shuttle body formed with a cavity adapted to house a spindle, a bridge piece in said cavity offering a funnel shaped seat for the bottom end of a spindle, a hook-shaped clip arranged near one end of said cavity, a toggle lever arranged to rock about an axis extending across said cavity, and operatively connected with said clip to pull and push it, respectively, in the longitudinal direction of said shuttle body and the spindle seat formed therein and to lock the spindle in its seat, and a spindle formed with a frusto-conical bottom extension fitting in the funnel-shaped seat in said bridge piece.

3. In a loom-shuttle in combination, a shuttle body formed with a cavity adapted to house a spindle, a bridge piece in said cavity offering a funnel shaped seat for the bottom end of a spindle, a hook-shaped clip arranged near one end of said cavity, a toggle lever arranged to rock about an axis extending across said cavity, and operatively connected with said clip to pull and push it, respectively, in the longitudinal direction of said shuttle body and the spindle seat formed therein and to lock the spindle in its seat, a spindle and a frusto-conical extension at the bottom end of said spindle fitting in the funnel-shaped seat in said bridge.

4. In a loom-shuttle in combination, a shuttle body formed with a cavity adapted to house a spindle, a bridge piece in said cavity offering a funnel shaped seat for the bottom end of a spindle, a hook-shaped clip arranged near one end of said cavity, a toggle lever arranged to rock about an axis extending across said cavity, and operatively connected with said clip to pull and push it, respectively, in the longitudinal direction of said shuttle body and the spindle seat formed therein and to lock the spindle in its seat, a spindle and a frusto-conical extension at the bottom end of said spindle fitting in the funnel-shaped seat in said bridge, said extension being formed with a transverse bore allowing the free end of said clip to pass through.

5. In a loom-shuttle in combination, a shuttle body formed with a cavity adapted to house a spindle, a bridge piece in said cavity offering a funnel shaped seat for the bottom end of a spindle, a hook-shaped clip arranged near one end of said cavity, a toggle lever arranged to rock about an axis extending across said cavity, and operatively connected with said clip to pull and push it, respectively, in the longitudinal direction of said shuttle body and the spindle seat formed therein and to lock the spindle in its seat, a spindle and a frusto-conical extension at the bottom end of said spindle fitting in the fun-

nel-shaped seat in said bridge, said extension being formed with a transverse bore allowing the free end of said clip to pass through and with a longitudinally extending guide groove allowing the free end of said clip to enter.

5. In a loom-shuttle in combination, a shuttle body formed with a cavity adapted to house a spindle, a bridge piece in said cavity offering a seat for the bottom end of a spindle, a hook-shaped clip arranged near one end of said cavity and a horse-shoe shaped toggle lever arranged to rock about an axis extending across said cavity, and operatively connected with said clip to pull and push it, respectively, in the longitudinal direction of said shuttle body and the spindle seat formed therein and to lock the spindle in its seat.

6. In a loom-shuttle in combination, a shuttle body formed with a cavity adapted to house a spindle, a bridge piece in said cavity offering a seat for the bottom end of a spindle, a hook-shaped clip arranged near one end of said cavity, a toggle lever arranged to rock about an axis extending across said cavity, and operatively connected with said clip to pull and push it, respectively, in the longitudinal direction of said shuttle body and the spindle seat formed therein and to lock the spindle in its seat, and an arm pivoted to said toggle lever near the fulcrum of said lever, said clip being mounted in said arm and being free to rock relative to same.

7. In a loom-shuttle in combination, a shuttle body formed with a cavity adapted to house a spindle, a bridge piece in said cavity offering a seat for the bottom end of a spindle, a hook-shaped clip arranged near one end of said cavity, a toggle lever arranged to rock about an axis extending across said cavity, and operatively connected with said clip to pull and push it, respectively, in the longitudinal direction of said shuttle body and the spindle seat formed therein and to lock the spindle in its seat, and an arm pivoted to said toggle lever near the fulcrum of said lever, said clip being mounted in said arm and being free to rock relative to same, said bridge piece being formed with two inclined faces adapted to serve as abutments for said arm and for said clip, respectively, when these parts assume their locking position.

8. In a loom shuttle in combination, a shuttle body formed with a cavity adapted to house a spindle, said body being formed near one end of said cavity with a seat for the bottom end of a spindle, a toggle lever near said seat arranged to rock about an axis extending across said cavity, and a hook-shaped clip operatively connected with and adjustable relative to said toggle lever, said clip being adapted to cooperate with said lever in pulling and pushing the spindle in the longitudinal direction of said shuttle body and to lock the spindle in said seat.

GEORG WIGET.
